(57) **CLAIM**

The ornamental design for a jewelry ornament, as shown and described.

DESCRIPTION

FIG. 1 is a top view of the jewelry ornament.

FIG. 2 is a left side view of the jewelry ornament.

FIG. 3 is a front view of the jewelry ornament.

FIG. 4 is a right side view of the jewelry ornament.

FIG. 5 is a bottom view of the jewelry ornament; and,

FIG. 6 is a rear view of the jewelry ornament.

The broken lines illustrate portions of the jewelry ornament that form no part of the claimed design.
